[57] CLAIM

The ornamental design for a container for feminine hygiene items, as shown and described.

DESCRIPTION

FIG. 1 is a front, top and side perspective view of the container for feminine hygiene items showing our new design in the partially open condition;

FIG. 2 is a front elevational view thereof;

FIG. 3 is a rear elevational view thereof;

FIG. 4 is a side elevational view thereof, the side opposite being a mirror image of the side shown in FIG. 4; and,

FIG. 5 is a top plan view thereof, the bottom being plane and unornamented.

FIG.1.

FIG.2.

FIG.5.

FIG. 3.

FIG. 4.
